UPHOLSTERED CHAIR OF MOLDED URETHANE FOAM

Bruce G. Hood, Marblehead, Mass., assignor, by mesne assignments, to Davidson Rubber Company, Incorporated, a corporation of Delaware

Filed June 24, 1963, Ser. No. 289,809

3 Claims. (Cl. 297—455)

This invention is an upholstered set member molded from low density urethane foam, such as a chair or sofa.

The upholstered seat member consists of an integral or monolithic core of rigid urethane foam defining the base, the back rest and at least one arm member. The body contacting surfaces of this core are covered with a well-bonded layer of soft, flexible and resilient urethane foam. The visible outer surfaces of the seat member are covered with a suitable tough covering not only for the purposes of appearance but also because the covering prevents local damage to and tearing of the urethane foam.

Besides its aesthetic appearance and comfortable upholstered nature, the seat member of this invention is characterized by the simplicity of its elements which greatly simplifies the manufacturing procedure and permits mass production. It is also characterized by its light weight while still having good abuse resistance and strength.

In a preferred design of this invention, the back rest and arm rest flow smoothly together to form a generally cup-shaped side and back supporting wall. This design is such that maximum advantage is taken of the structural strength of the urethane foams.

The nature and advantages of the seat member of this invention will become clear from the following description and examples made with reference to the drawings attached to and forming a part of this specification.

In the drawings:

FIG. 1 is a perspective view of a completed chair;

FIG. 2 is a front elevational cross-section view taken along line 2—2 of FIG. 1;

FIG. 3 is an enlarged view of a corner section of the supporting core of the seat member showing a densified outer skin;

FIG. 4 is an enlarged cross-sectional view of the lower edge of the core showing inclusion in the core of a tacking strip for purposes of anchoring the upholstery covering; and

FIG. 5 is an enlarged cross-sectional view of the bottom edge of the core showing inclusion in the core of strengthening and fastening means for permitting attachment of the supporting legs to the chair.

Rigid urethane foams have, generally speaking, been regarded as being essentially weak, friable materials useful mainly for filling voids or where lightness and insulation values are important, but not strength. In the seating member of the present invention maximum advantage is taken of the strength of a rigid urethane foam core in cooperation with a surface covering of a soft flexible urethane foam. In bulk, rigid urethane foams can be quite strong but if a high local pressure is applied to the surface of a rigid urethane foam it tends to collapse and leave an indentation. In the present invention the wear receiving or body supporting surfaces of the urethane core member are protected by being covered with a resilient but fairly strong layer of flexible urethane foam. This

2

flexible urethane foam covering is tougher than the rigid urethane foam core and serves to distribute any pressure applied to it over a wider area of the rigid urethane core. The flexible covering has, of course, more impact resistance than the urethane core and serves to prevent damage to the core member when it is forcibly struck. The flexible urethane covering is well bonded to the wear receiving surfaces of the urethane core to prevent slippage and looseness and to have the urethane core in turn impart strength to the flexible urethane covering.

In addition to the cooperative relationship between the flexible covering and the rigid core, the wear receiving surfaces of the upholstered unit are additionally covered with a strong decorative outer covering such as a vinyl covering or one made from fabric. Flexible urethane foams have a relatively low tear resistance or resistance to puncturing such as might be occasioned by being poked with a pencil. The outer tough covering has for its purpose the protection of the urethane foam from this type of abuse.

Table I presented hereinafter summarizes the preferred properties of the urethane foams used in the practice of this invention, and gives examples thereof. Specific formulations are presented in Table II.

Referring to the drawings, the seat member of this invention consists of a molded core 10 of rigid polyurethane foam. This core defines the base 10a of the seat member, the arm rest 10b and the back rest. The hole of the core is integral or monolithic. Since the rigid urethane foam is incapable of resisting a high localized pressure, a reinforcing member 11 which extends over a considerable portion of the underside of the base is integrally molded into the core structure and is adapted to receive the supporting legs 12 for the chair. Reinforcing element 11 may be a solid wood piece as shown in FIG. 2, or as shown in FIG. 5 can be a relatively heavy screen 11a which also can be used to receive screws 13 by which legs 12 are attached.

The molding of the core is quite straight forward. The formulation given in Table II is a room temperature curing formulation. An enclosed mold of suitable design is fabricated and the urethane ingredients are mixed and promptly injected into this mold and the mold is closed. Foaming occurs immediately with some exotherm. With the formulation of Table I the reaction will be complete in about twenty minutes for this size structure. One feature of this invention is the provision for a tough skin on the outer surfaces of the core having a higher density than the foam in the interior of the core. This is shown in FIG. 3. The denser skin is shown at x and the lighter interior core at y. Skin x has a thickness of about 0.06 inch and is at least two times the density of the core y. This is achieved by chilling the outer surfaces of the mold so that the expanding foam when it contacts the interior walls of the mold is chilled causing the blowing agent either to remain liquid or to exert a lesser expansive force.

As indicated previously, the core in itself will not take too much abuse on its wear receiving surfaces. For this reason and for the purpose of providing an upholstered feeling, the wear receiving or body supporting surfaces of core 10 are covered with a resilient flexible urethane foam 15, the formulation of which is given in Table II. This layer 15 can be derived from slab stock if the surface of the core 10 is amenable to being covered in this manner. A good adhesive such as Empire Adhesives R-1041-2 should be used to secure tight bonding of the

covering to the core. The layer 15 can also be contour molded in a suitable mold if desired. A third way of applying covering 15 is to remove core 10 from its mold and place it in a larger mold that defines the contour for covering 15. The flexible urethane foam ingredients can be injected in the mold and the foaming and bonding can occur in place.

Considering the low density of the foams used in the seating member of this invention, the minimum cross-sectional thickness of any portion of the core should not be less than 2.50 inches in order to have adequate strength. The minimum thickness of the flexible padding in any cross-section should be 0.75 inch. This is not only from the standpoint of resiliency and comfortable feeling but also to provide sufficient depth to permit the flexible foam layer 15 to distribute local pressure more uniformly on the core.

The completed unit is covered on all its visible surfaces, i.e., except on the underside, with a fabric of synthetic fabric covering 16. The fabric is mounted by stretching it over the chair surfaces and attaching it to the underside of the base. In the preferred embodiment of this invention the underside of the base has tacking strips 17 (see FIG. 4) integrally molded therein for this purpose. This covering can be adhesively attached to the flexible urethane covering 15 as required to define contour such as at surfaces 20 and 21.

The urethane cushion element 15 could, of course, extend across the upper surface 21 of core 10 to provide a sitting pad. In the design shown, however, a separate cushioning element 23, also molded of flexible urethane foam and covered with fabric 16, is used for this purpose. It matches the contour of the basic chair unit. In this arrangement, fabric 16 need not extend over all of surface 21, although this is preferred.

The particular design of chair shown in the drawings is preferred because it takes maximum advantage of the strength offered by the urethane foams. It will be noted that when viewed from the top it is of generally semi-circular configuration with the back rest coming up to about the mid-point of the person sitting in the chair. The back rest and arm members smoothly flow together to form one continuous integral unit. The top surfaces of the arms are downwardly inclined towards the front of the chair. The supporting core member when viewed in cross-section from the front has the appearance of an upwardly opening thick-walled channel with the walls being outwardly inclined. The inner side walls of the arm rest and back rest have a funnel shape.

It can be appreciated that this semi-circular configuration permits the stresses on the chair occasioned by a person sitting in it and leaning back to be relatively uniformly distributed over the foam structure. The upper horizontal surface of the back rest-arm rest configuration provides adequate comfortable support for the arms of a person sitting in the chair. This clean, modernistic free flowing design is considered to be a distinguishing feature of this invention and represents a preferred embodiment thereof.

TABLE I

Properties of foamed urethanes

	Range	Example
Rigid Core (ASTM Test):		
Density, lbs./ft. ³	4 to 20	5 to 6
Tensile strength, p.s.i. (D638)	20 to 40	30 to 40
Compression strength, p.s.i. (yield point)	15 to 30	20 to 25
Flexural strength, p.s.i. (ASTM-D790)	20 to 60	30 to 40
Minimum section thickness, inches	2.5 to 7	3 to 7
Cushioning Layer:		
Density, lbs./ft. ³	0.9 to 6	1.5 to 4
Elongation, percent (D638)	100 to 350	150 to 250
Tensile strength, p.s.i. (D638)	5 to 40	10 to 30
RMA firmness, 25% deflection	5 to 35	15 to 25
Resiliency (Nopco tester ball rebound), percent	40 to 60	45 to 50

TABLE II

Urethane formulations

Core formulation (parts by weight):	
Polyglycol-A ¹	95.0
Toluene diisocyanate ²	72.5
Blowing agent ³	25.0
Lubricant ⁴	2.0
Curing agent ⁵	0.5
Cushioning layer formulation (parts by weight):	
Polyglycol-B ¹	100.0
Toluene diisocyanate ²	46.3
Blowing agent ³	3.0
Lubricant ⁴	2.0
Curing agent ⁵	0.24
Tin catalyst ⁶	0.24
Water	3.4

¹ Polyglycol-A (Atlas Powder G-2410) is a sorbitol based hexanol having a hydroxyl number of approximately 490.

² Polyglycol-B (Wyandotte Chemical Plurecal TP2540) is a polyoxypropylene triol derivative of trimethylolpropane having a molecular weight of 2670 and a viscosity of 440 cps. at 25 degrees C.

³ A commercial mixture of 80% of the 2,4 isomer and 20% of the 2,6 isomer.

⁴ Difluoro-dichloro methane (Freon-11).

⁵ Silicone (Union Carbide Corp. Silicones L-520).

⁶ T-9 (Metal & Thermit Corp.).

Other rigid and flexible urethane formulations can, of course, be used so long as they meet the physicals given in Table I.

Having described this invention what is sought to be protected by Letters Patent is succinctly set forth in the following claims.

I claim:

1. An integral upholstered seat member comprising a supporting monolithic core of rigid urethane foam free from any internal upwardly extending supporting means, of substantially uniform internal density and defining a base, a back rest and an arm rest, the underside of said base having molded therein a reinforcing element extending over substantial area of the underside of said base, a soft flexible layer of urethane foam bonded to the body contacting surfaces of said back rest and said arm rest and a decorative flexible and protective covering over the visible surfaces thereof other than the underside of said base, said rigid urethane foam having a density in the range of 2.5 to 5 lbs. per cubic feet, a flexural strength in the range of 20 to 60 p.s.i., and a minimum thickness in cross-section at any point of 2.5 inches, and said soft flexible layer having a density in the range of 1.5 to 6 lbs. per cubic foot, an elongation in the range of 100 to 350 percent, a tensile strength in the range of 5 to 40 p.s.i. and a RMA firmness at 25% deflection in the range of 5 to 35.

2. The seat member of claim 1 having two arm rests on either side of said base and wherein said core when viewed in front cross-section has the shape of an upwardly opening thick wall channel, and wherein the upper surface of said arm rest and back rest form a smooth flowing generally circular shape such that the inner side surfaces of the arm rest and back rest walls have a cup shape.

3. The seat member of claim 1 wherein a similarly covered seat cushion of flexible urethane foam is located on the upper surface of said base and wherein supporting legs are attached to said reinforcing element.
